UNITED STATES PATENT OFFICE.

BENJAMIN K. FISHER, OF ST. LOUIS, MISSOURI.

ADDING-MACHINE.

1,220,737.

Specification of Letters Patent. Patented Mar. 27, 1917.

Application filed March 16, 1915. Serial No. 14,701.

To all whom it may concern:

Be it known that I, BENJAMIN K. FISHER, a citizen of the United States, residing at St. Louis, State of Missouri, have invented 5 certain new and useful Improvements in Adding-Machines; and I do hereby declare the following to be a full, clear, and exact description of the invention, such as will enable others skilled in the art to which it 10 appertains to make and use the same.

This invention relates to adding machines of that type wherein a base-board is provided with a series of numbers to be added and has rotatably mounted relatively thereto 15 a second board, preferably in the form of a disk, bearing a series of numbers indicative of the totals or sums resulting from the addition of selected numbers of the series of the base-board.

20 In carrying out my invention it is my purpose to provide a device of this character through the medium of which the arithmetical process of addition may be easily, rapidly and accurately accomplished.

25 Another object of the invention is to provide a device by means of which extended series of numbers may be added or totaled, one column at a time, provision being made for carrying a number from one column to 30 the next, as is usual in the process of addition.

It is also my purpose to provide an adding machine which will embody the desired 35 features of simplicity, efficiency and convenience, and which, having but comparatively few parts, may be manufactured and marketed at relatively low cost.

With the above recited objects and others 40 of a similar nature in view, my invention consists in the construction, combination and arrangement of parts set forth in and falling within the scope of the appended claims.

In the accompanying drawings:

45 Figure 1 is a top plan view of an adding machine embodying my invention.

Fig. 2 is a vertical section taken there- 40 through on line 2—2 of Fig. 1.

Fig. 3 is a detail perspective view of the indicator slide.

Fig. 4 is a vertical sectional view taken 50 on the line 4—4 of Fig. 1.

Before entering into a detail description of my invention, I will briefly state that in the present instance it embraces among other features, a base-board upon which is 55 rotatably mounted a traveling dial or disk. The base-board is provided with a segmental column of numbers, in the present instance, running from 1 to 27, although I wish it to be understood that the series of numbers 60 in this column may be increased or decreased as desired, depending of course upon the size of the board. This column for the sake of convenience will hereinafter be termed the "unit column" and it contains the numbers 65 to be added. The upper surface of the rotary disk is marked with a numeral bearing dial, and the numerals thereon are to indicate the sums or totals obtained by adding the numerals or figures of the unit 70 column, the total numerals being arranged in circular, concentric columns, with the column of numbers adjacent the center of the disk starting with zero and ending with 75 44, and the adjacent column starting with the numeral 45 and ending with the numeral 92, while the third column from the center of the disk begins with the numeral 93 and ends with the numeral 140. This method of marking the numerals in the columns 80 continues throughout the entire scale. Of course the extent of the series of numbers in each column depends upon the dimensions or size of the circular space in which they are arranged, as it will be readily understood that as many numbers as may be convenient 85 may be contained in each column.

The alining numbers in the various columns, or those numbers which are in line, from the inner toward the outer edge of the 90 dial, do not run radially relative to the center of the revolving disk, but are arranged in lines tangential to the center so that during an adding operation, the desired total number will always be brought directly beneath the pointer on the indicator slide, which operates above the numerical dial of the disk. Should the total of a column of 95

figures exceed the largest number marked in a column above which the pointer of the indicator slide lies at the time of the adding operation, such slide is shifted or moved to 5 the next outward column by means of a member carried by the revolving disk as will hereinafter appear.

Referring now to the accompanying drawings in detail, A indicates the base-board of 10 the machine, which may be of any suitable material such as pasteboard, cardboard, wood or metal. Preferably here the base-board is made of stiff pasteboard having a top face or covering of thin sheet metal. 15 Extending upward from the base-board is a stop B, and in the present instance this stop is preferably formed by striking up the metal which constitutes the top covering of the board. The top surface of the board is 20 marked with a relatively large segmental strip C which is preferably made by painting with a different color from the top surface of the board. This strip forms a segmental column in which I mark a series of 25 numerals, in the present instance, running consecutively from 1 to 27, the numeral 1 being arranged nearest the stop, while the numeral 27 is at the opposite end of the column as will be readily understood by referring to Fig. 1. This series of numerals is 30 indicated by the letter C', and the numbers thereof constitute the numbers to be added, one at a time, and therefore I have termed this the "unit column". The letter D indicates a rotatable disk which is preferably 35 made of metal and is mounted to turn upon the pivot stud E extending upward from the center of the base-board and through the center of the disk, a small washer F 40 rounding the stud and bearing against the central portion of the top face of the disk. A spacing sleeve G is then threaded on the shank of the stud and forms a support for the inner end of the indicator slide-bar H 45 which is perforated to permit the passage of the upper end of the stud, a small nut J being threaded onto the end of the stud to hold the slide-bar in place. This slide-bar extends across the top of the disk and has its 50 downturned end K fastened to the base-board adjacent one corner thereof by means of the screw L and the nut M. The slide-bar is thus elevated above the disk so that the latter may revolve freely therebeneath, 55 and this bar is preferably formed of metal, such as a strip of brass. Shiftable longitudinally of this bar H is an indicator slide N which is preferably formed of a single blank of metal cut to provide spaced lugs n at the 60 longitudinal side edges of the slide, the body of the strip constituting the slide resting against the under face of the bar H, while

the lugs are bent around the side edges of the bar and inward upon the top of such bar, thereby holding the slide to the bar while 65 permitting such slide to be readily shifted. The blank is further cut and bent to provide the indicating finger or pointer P, while a series of spaced tongues Q inclined transversely relative to the body of the slide are 70 provided thereon for the purpose hereinafter mentioned. These tongues are parallel to each other and are so arranged that one tongue lies above each circular column of figures or numerals, upon the dial. The top 75 face of the rotary disk is marked with a circular dial R divided in the present instance, into concentric spaces or columns S, S¹, S², S³, S⁴, S⁵, S⁶ and S⁷. The innermost column S is provided with a series of numerals 80 running consecutively from zero to 44; the column S¹ has numerals running from 45 to 92; the column S² has numerals running from 93 to 140; the column S³ has numerals running from 141 to 188; the column S⁴ has 85 numerals running from 189 to 236; the column S⁵ has numerals running from 237 to 284; the column S⁶ has numerals running from 285 to 332; and the column S⁷ has numerals running from 333 to 380, while the 90 outermost or segmental column S⁸ has numerals running from 381 to 400. Thus, I provide sufficient numerals on the present machine to provide any total for a single column of figures which will not exceed 400, 95 but it will of course be understood that the numbers or figures for the totals may be increased or decreased as desired.

Arranged adjacent the periphery of the numeral dial R of the rotary disk is a circular column T having a series of consecutive numbers running from zero to 40 marked thereon and the numbers in this column are employed for the operation of carrying a number from one column of figures to another as is common in the process of addition. Extending upward from the rotary disk adjacent the periphery thereof are small lips U, these lips being spaced apart and arranged in a circular series, one 100 lip being opposite each of the radial lines of figures on the dial. It is to be understood that these lips form finger grips for enabling the rotary disk to be turned and these lips are preferably struck up from the material of the disk. Mounted upon the rotary disk, but outside of the columns of numerals thereon is a slide shifting strip W which 105 extends at an angle to the circular numeral dial, and the purpose of this strip is to 110 shift the slide from one concentric column of numerals to the next outward column when the necessity arises, as will hereinafter appear.

In order to make clear the operation of my device, I will give a concrete example in addition.

Assuming for instance, it be desired to 5 add three columns of figures as follows:

10	809
	674
	534
	194
	360
	447
	656
	875
15	587
	940

The disk is first turned until the zero indication in the column T is directly beneath the pointer or finger of the indicator slide, 20 the slide at this time being moved inward toward the center of the disk on its bar as far as possible. This will bring the zero number in the carrying column T directly beneath the stop B on the base-board. As 25 we first add the unit column of the sum or that to the right, following the usual practice, the operator now places his finger in the space between the two lips opposite the numbers 7 and 8 of the carrying column T, 30 this space being directly opposite the numeral 7 in the unit column, and pulls the rotary disk around until his finger strikes the stop. He then places his finger in the space between the two lips opposite the numeral 5 of the unit column and repeats the 35 operation of bringing the disk around until his finger strikes the stop. He proceeds with the same operation through the remaining numerals, in the first or unit column of the sum. Now it will be noted that when all the numerals in the first or unit column of the sum given have been added, 40 they total 46 and when the adding of this column has been completed on the machine 45 the pointer or finger of the indicator slide will point to 46 on the numeral dial having the sums or totals marked thereon, this number 46 appearing in the column S¹. The slide has moved outward from the column 50 S to the column S¹ because after the numeral 44 or the highest figure in the column S was reached, the rotation of the disk to this point had brought the slide-moving strip W into contact with one of the tongues 55 depending from the slide and the continued rotation of the dial had forced this strip into engagement with the tongue and the strip in passing the tongue shifted the slide outward one step or column from the column S into the column S¹. The machine having shown that the total of the unit column is 46, the operator writes this sum

down on a piece of paper and draws a line through the digit 4 as this is the number to be carried. He now turns the disk so that 65 the numeral 4 of the carrying column is in line with the stop. The slide is now moved back so indicator is over the column S again and the operation of adding the second column proceeds as before. It will be seen 70 that the total of the second column will be 52 and the operator places this on the paper as follows:

46		
52		75

The digit 5 is of course to be carried and this is done as before. The third column is now added and totals 60 and this is placed on the paper as follows:

4 6	Col. 1
5 2	Col. 2
6 0	Col. 3
6 0 2 6	Total

80

85

The result is a total 6026 in the operation of the machine.

It will be understood that much time can be saved by taking groups of figures, thus 90 1, 3 and 4 can be added as 8, or 6—7—5 as 18.

One important advantage of the invention is that when two or more numbers have been added together, the pointer of the indicator slide will always point to a single number 95 reading the exact total of the numbers added. In other words, it is unnecessary to refer to two or more numbers or to shift from one point on the dial to another to ascertain the total, as a single number always 100 represents such totaled or added sum.

While I have herein shown and described one particular embodiment of my invention, I wish it to be understood that I do not confine myself to all the precise details of construction herein set forth by way of illustration, as modification and variation may be made without departing from the spirit of the invention or exceeding the scope of the appended claims.

What I claim is:

1. The combination of a base having a column marked with numerals to be added, a rotary disk mounted on the base and having a column marked with numerals to be carried and further having a scale dial thereon divided into concentric columns, each column having a series of consecutive total numbers marked thereon, the corresponding numerals of the various columns being disposed in rows in line with respective numerals to be carried, and a circular row of upstanding lips fixed to the disk adjacent the periphery thereof and disposed

105

110

115

120

respectively in line with the rows and the numerals to be carried.

2. An index slide for disk adding machines formed from a metal blank having a plurality of pairs of opposite lateral arms bent inwardly to embrace a supporting bar and further having a plurality of downwardly directed tongues struck therefrom, and a total indicating pointer on the slide.

10 3. The combination of a base having a column marked with numerals to be added, a rotary disk mounted on the base and having a column marked with numerals to be carried and further having a scale dial thereon divided into concentric columns, each column having a series of consecutive total numbers marked thereon, the corresponding

numerals of the various columns being disposed in rows in line with respective numerals to be carried, a circular row of upstanding lips fixed to the disk adjacent the periphery thereof and disposed respectively in line with the rows and the numerals to be carried, an indicator slide mounted above and shiftable over the scale, and means carried by the disk for shifting the slide from one column of numerals on the scale to an adjacent column of numerals. 20 25

In testimony whereof, I affix my signature in the presence of two witnesses.

BENJAMIN K. FISHER.
